WARP MACHINE

Paul Schönfeld, Chemnitz, Germany

Application June 14, 1940, Serial No. 340,427
In Germany May 13, 1938

2 Claims. (Cl. 139—100)

This invention relates to warp machines, and particularly to a drive for the warp beam thereof.

It is known to provide warp machines with a warp beam drive substantially comprising a self-locking driving device that can be started and stopped by a clutch coupling and a warp tension roller which is moved by the warp and, by controlling the coupling in dependence upon the consumption of the warp, starts or stops the self-locking driving device.

In the known warp beam drives of this class the warp tension roller is formed by the shaft guiding the warp and pressed against it by spring action. At normal tension of the warp the shaft holds the coupling of the driving device and thereby also the driving device itself in inoperative position. When the tension of the warp due to the consumption thereof increases, the shaft is adjusted by the warp against the action of the spring thereof and initiates the engagement of the coupling and the starting of the self-locking driving device for the beam. Each starting of the beam driving device presupposes therefore an increase in warp tension, and this increased tension, immaterial when non-yielding and inelastic goods are concerned, has serious results in case of, say, rubber warps, because it means irregular working and the production of unsightly and even useless fabrics.

According to the invention, this trouble is overcome by controlling the coupling by a weighted roller loosely disposed in a sag of the rubber warp and lifting a feeler after reaching a predetermined position whereby engagement of the coupling is effected.

Although the warp tension roller of a drive according to the invention is also moved into operative position by the warp during the consumption thereof, this is done without requiring an increase in warp tension, since the roller is loosely suspended in a sag of the warp. The term "tension roller" is retained only because the roller serves for imparting to the warp the necessary initial tension and equalizing the stressing of the various threads. The feeler acted upon by the roller in the predetermined position to throw in the coupling does not require for lifting an expenditure of energy involving increased warp tension, so that the drive according to the invention is actuated completely independently of the warp tension.

It is not new of course in the art to loosely arrange a tension roller in a sag of the warp and to use the roller for controlling the beam drive.

The known constructions lack, however, a self-locking beam drive as well as a coupling for starting and stopping the drive, and there is, moreover, no feeler, since the tension roller itself by its own weight acts as beam drive. The beam simply has a brake or pawl-controlled locking mechanism which is rendered inoperative when the roller has reached a certain elevated position so as to permit free motion of the beam and its rotation by the roller descending by its own weight to a position at which it releases again the brake or other locking mechanism for stopping the beam. The unavoidably sudden release of the brake or other mechanism causes too rapid motion of the beam and brings about an abrupt drop in tension in elastic warps. Inversely, restarting of the beam involves a temporary increase in tension, so that this known beam drive is not suited for elastic warps.

20 The invention is illustrated by way of example in the accompanying drawing, in which

Figure 1 is a side view of a beam for rubber warps with a tension roller arranged in a sag of the warp and a feeler disposed in the roller path;

25 Fig. 2 shows the equipment of the beam with a self-locking driving device and a coupling associated therewith; and

Fig. 3 shows on an enlarged scale the control of the coupling.

30 The warp beam 2 for the rubber warp 1 is fitted with a self-locking driving device comprising a worm 16 on a shaft 14 and a worm wheel 15 on the beam shaft. The shaft 14 receives its motion from a shaft 8 by means of a chain 12 and

35 two sprockets 11, 13. The self-locking driving device 15, 16 can be started and stopped by a coupling 6, 7, the member 7 thereof being loosely positioned on the shaft 8 and secured against axial displacement whilst the clutch member 6 is

40 arranged thereon so as to be axially displaceable but non-rotatable. The clutch member 6 is provided with a sprocket 9 and can be rotated by means of a chain 10 to rotate the shaft 8. A spring 17 keeps the two members 6, 7 forming a known pin coupling apart. The coupling 6, 7 is controlled by a tension roller 3 which is moved up and down in dependence upon the consumption of the warp in a sag of the latter and whose

45 weight may be varied by weights 4. In the path of the roller 3 a feeler 5 is positioned and lifted by the roller 3 at a predetermined position to throw in the coupling 6, 7. As shown in Figs. 1, 3, the feeler 5 comprises a bar disposed on a rocking shaft 19 provided with a cam 18 and a roll

20 which abuts against the side of the coupling member 6, the arrangement being such that lifting of the feeler 5 by the roller 3 causes the cam 18 or its roll 20 to push the movable coupling member 6 into closing position.

The invention is not restricted to the construction shown and described, since it is obvious that various changes can be made in the form of the coupling controlling the self-locking driving device as well as in the device itself and with respect to the feeler and the way it acts upon the coupling without departing from the scope thereof.

I claim:

1. A warp beam drive in warp machines, comprising a warp beam equipped with an elastic warp, a beam shaft, a self-locking driving device including a shaft, a worm disposed on said shaft and a worm wheel on the beam shaft, means for

driving said shaft, a coupling arranged on said shaft driving means and having a movable member for starting and stopping the beam drive, a tension roller disposed in a sag of the warp and capable of up and down motion in response to the consumption of warp for controlling the coupling, means for varying the weight of the tension roller, and a feeler positioned in the path of the tension roller and lifted by said roller at a predetermined position to actuate the coupling.

2. A warp beam drive according to claim 1, comprising a rocking shaft supporting the feeler and a cam with roll disposed on said shaft, said roll contacting with the movable member of the coupling and pushing it into closing position when said feeler is lifted by said tension roller.

PAUL SCHÖNFIELD.
